CLAIM

The ornamental design for a desk lamp, as shown and described.

DESCRIPTION

Figure 1.1 is a top front perspective view of a first embodiment of a desk lamp showing the claimed design;

Figure 1.2 is a front elevation view thereof;

Figure 1.3 is a rear elevation view thereof;

Figure 1.4 is a right side elevation view thereof;

Figure 1.5 is a left side elevation view thereof;

Figure 1.6 is a top plan view thereof;

Figure 1.7 is a bottom plan view thereof;

Figure 2.1 is a top front perspective view of a second embodiment of a desk lamp showing the claimed design;

Figure 2.2 is a front elevation view thereof;

Figure 2.3 is a rear elevation view thereof;

Figure 2.4 is a right side elevation view thereof;

Figure 2.5 is a left side elevation view thereof;

Figure 2.6 is a top plan view thereof; and

Figure 2.7 is a bottom plan view thereof.

The broken lines in the figures show portions of the desk lamp that form no part of the claimed design.
